UNITED STATES PATENT OFFICE

94,620

DESIGN FOR A LIGHTING FIXTURE PLATE OR SIMILAR ARTICLE

Samuel Perla and Paul Siptrott, New York, N. Y.;
said Siptrott assignor to said Perla

Application December 20, 1934, Serial No. 54,522

Term of patent 3½ years

To all whom it may concern:

Be it known that we, Samuel Perla, a citizen of the United States of America, residing in the county of Kings, city and State of New York, and Paul Siptrott, a citizen of the Republic of Germany, residing in the city, county, and State of New York, have invented a new, original, and ornamental Design for a Lighting Fixture Plate or Similar Article, of which the following is a specification, reference being had to the accom-

panying drawing, forming a part hereof. In the drawing:

Fig. 1 is an inverted plan view of the lighting fixture plate or similar article, and

Fig. 2 is a side elevational view of the same.

I claim:

The ornamental design for a lighting fixture plate or similar article as shown.

SAMUEL PERLA.
PAUL SIPTROTT.
